FINGER SUPPORT FOR NAIL POLISH
APPLICATION

Philip Libson, Brooklyn, N.Y.

Application November 24, 1947, Serial No. 787,806

4 Claims. (Cl. 132—73.5)

1 The present invention relates to a finger support for nail polish application.

Heretofore in applying polishing liquid to the finger nails, it has been the practice to place a small bottle or vial of polishing liquid on a bureau or dressing table and to extend the fingers of one hand in the air while applying the liquid to the finger nails of this hand by means of a soft brush held in the other hand. During the interval between immersion of the brush in the polishing liquid and the application of said liquid to the finger nails, it often happens that the liquid will drop from the brush and stain or otherwise damage the wearing apparel of the user and likewise spot or disfigure furniture and the like. In some cases the polishing liquid will tend to evaporate or partially solidify on the brush, thus necessitating repeated immersion of the brush in the polishing fluid in order that the liquid will have the desired fluidity to permit proper spreading or coating thereof on the finger nails. Moreover, it is difficult to apply the polish accurately and exactly within the desired limits to the finger nails of the unsupported hand, which, after a short time, becomes tired and, consequently, unable to maintain the fingers motionless in the same position. Furthermore, when the bottle is supported on a dressing table and the brush is immersed into and withdrawn from the bottle, it frequently happens that the brush will overbalance or upset the bottle and spill the contents thereof over the highly polished surface of the dressing table, thereby not only damaging the latter but also causing a total loss of the polishing liquid.

One object of the invention is to provide a support on which each individual finger may be placed to be firmly supported and accurately located in the immediate vicinity of the mouth of the nail polish bottle in order to facilitate the transfer of polish by means of the usual brush from the polish bottle to the finger nail and to eliminate the danger of polish dropping from or solidifying on the brush during said transfer.

Another object of the invention is to steady the nail polish bottle on its supporting surface, such as a table or dresser top, while the brush is immersed into and withdrawn from the polish bottle.

A still further object of the invention is to provide a simple, inexpensive and aesthetically attractive finger support for the application of nail polish.

These and other objects which will appear more clearly as the specification proceeds are

accomplished according to the invention by the arrangement and combination of elements set forth in the following detailed description, defined in the appended claims and illustratively exemplified in the accompanying drawings in which

Fig. 1 is a perspective view of a finger support according to the present invention applied to a nail polish bottle of substantially triangular cross-section,

Fig. 2 is a top plan view of the arrangement according to Fig. 1,

Fig. 3 is a sheet metal blank from which the finger support shown in Figs. 1 and 2 is obtained by bending and

Figs. 4, 5 and 6 are, respectively, perspective views of three modifications of the finger support according to the invention.

Referring now to the drawings and first to Figs. 1 and 2, 11 denotes a nail polish bottle of substantially triangular cross-section closed by a cap 12 which is omitted in Fig. 2 to show the bottle mouth 13.

Applied to the bottle 11 is a finger support and bottle holder formed from a sheet metal blank as illustrated in Fig. 3. The blank comprises an elongated rectangular strip portion 13a of a length and width to form, upon being bent at right angles on a transverse line 14 (shown as a broken line) a short distance from one of its ends, a platform 15 to support an individual finger tip and a vertical support wall 16 integral with said platform 15 on said bending line 14 and having a height corresponding approximately to that of the bottle 11. The platform 15 may be grooved as shown in Figs. 1 and 2 to permit the exact location of a finger tip resting on the platform.

A narrow strip 17 projects at right angles from one side edge of the elongated strip portion 13a at approximately equal distances from the ends support of the wall 16. The strip 17 has a length sufficient to form a complete loop about the body 11 of the nail polish bottle. The free end 17a of the strip 17 may be secured, for instance by soldering, to the opposite side edge of the elongated strip portion 13a. Two lugs 18 project from the opposite side edges of the strip portion 13a at the lower end of the vertical support wall 16 and are bent to embrace the bottle as shown in Fig. 1.

When the blank 13a is bent as described and applied to the bottle 11, the vertical support wall 16 is disposed in a plane tangential to one of the flat walls of the bottle 11 and the finger supporting platform 15 is disposed in the vicinity

of the bottle mouth 13 and substantially in the same horizontal plane as the latter.

A finger placed on the platform 15 is securely positioned so close to the bottle mouth that the transfer of nail polish from the bottle mouth to the finger nail can be effected easily and accurately without any danger of nail polish dropping from the brush or drying on the brush. Moreover, the bottle 11 itself can not be upset when the brush is immersed or withdrawn because it is steadied and held in place by the loop 17 and lugs 18 integral with the vertical wall portion 16 and the platform 15 on which latter the finger rests, thus holding the entire assembly securely in position.

A simplified embodiment of the invention is shown in Fig. 4 in which the platform 25 is integral with a short vertical wall portion 26 extending downwardly from one of its edges and carrying a spring clip 27 which projects from the wall portion 26 in the direction away from the platform 25 and which serves to embrace the neck of the bottle 11. When the support according to Fig. 4 is applied to the bottle 11, the lower edge of the wall portion 26 rests on the shoulder of the bottle 11.

In the further embodiment of the invention, shown in Fig. 5, a platform 35 is integral at one edge thereof with a short downwardly extending vertical wall portion 36 adapted to rest with its free lower edge on the shoulder of a bottle and carrying by means of a hinge 37 a spring clip 38. On its opposite edge, the platform 35 is integral with a vertical wall portion 39 which extends downwardly for a distance approximately equal to the height of the bottle and serves to steady the arrangement against upsetting due to the pressure of a finger on the platform 35. In this arrangement, the spring clip 38 may be folded from the position shown in Fig. 5, in which it projects at right angles from the vertical wall portion 36, into a position substantially in the plane of the wall portion 36 to facilitate storing and shipping of the device.

The invention may also be realized in a very simple arrangement as shown in Fig. 6. A platform 45 forms the top of a rectangular column 46 consisting for instance, of sheet metal, china, plastic or the like. The platform 45 at the top of column 46 is disposed at a level approximately equal to the height of an average nail polish bottle and the device shown in Fig. 6 may simply be placed next to a bottle. The vertical walls of the column 46 make it possible to bring the platform 45 very close to the bottle mouth 13 so that the danger of nail polish dropping from the brush or evaporating on the brush is successfully avoided.

It should be understood that finger supports according to the present invention may be made from sheet metal, cardboard, plastic or any other suitable material and that they may be constructed in the form of scored blanks which can be stored and shipped in a limited space and can be folded or bent to the desired configuration prior to being used.

It will also be understood that the invention

is applicable to a nail polish remover bottle, as well as to a nail polish bottle.

I claim:

1. A finger support for use with a nail polish bottle to facilitate the transfer of polish from the bottle to a finger nail and to steady the bottle during the immersion and withdrawal of the brush, comprising a substantially horizontal platform shaped to support an individual finger tip, a support for said platform including a substantially vertical wall portion extending downwardly from one edge of said platform for a distance approximately equal to the height of a nail polish bottle and adapted to be located in a plane tangential to a wall of the nail polish bottle, and a loop element secured to said vertical wall intermediate its ends and at a distance from said platform edge exceeding the height of the neck of a nail polish bottle, said loop element projecting from said vertical wall in a horizontal plane away from said platform and being shaped and dimensioned to be slipped over and to embrace the body of a nail polish bottle to attach the finger support to such bottle.

2. A finger support as claimed in claim 1 including lugs projecting from the side edges of said vertical wall portion near the lower end thereof to embrace the body of a nail polish bottle near its bottom.

3. The combination of a nail polish bottle having a flat vertical wall portion and a finger support including a vertical sheet material element extending in a plane adjacent said flat bottle wall from the bottom of the bottle to the level of the bottle mouth, a loop secured to said vertical element and embracing the body of the bottle intermediate its upper and lower ends, and a horizontal platform integral with said vertical element at the upper edge thereof and extending away from said bottle mouth.

4. A combination, as claimed in claim 3, including a pair of lugs on the side edges of said vertical element near the lower end thereof and extending at angles to said vertical element to embrace the body of said bottle near its bottom.

PHILIP LIBSON.
